United States Patent Office.

S. J. GENUNG, OF WATERLOO, NEW YORK.

Letters Patent No. 94,486, dated September 7, 1869.

IMPROVED EXTENSION-TABLE SLIDE.

The Schedule referred to in these Letters Patent and making part of the same.

To all whom it may concern:

Be it known that I, S. J. GENUNG, of Waterloo, in the county of Seneca, and State of New York, have invented a certain new and useful Improvement in Extension-Table Slides; and I do hereby declare that the following is a full and exact description thereof, reference being had to the accompanying drawings, making part of this specification, in which—

Figure 1 is a perspective view of a set of extension-table bars, with my improvement attached.

Figure 2, a cross-section of the same.

Figure 3, a perspective view of one of the slides.

Like letters of reference indicate corresponding parts in all the figures.

My invention consists in a peculiar construction of the slides proper, whereby tongues are made to project down between the wooden bars, to keep them apart, and thus prevent friction; and a dovetail or wedge-shaped lug is made to serve as the attachments of the slides to the wood, instead of screws, thereby avoiding expense and labor.

The invention further consists in the combination, with such slides, fastening vertically upon the top and bottom of the bars, of a central tongue arrangement of slides for completing the construction, the whole as hereinafter set forth.

In the drawings—

A A A represent the ordinary extension-bars, arranged in the usual manner, except that a central groove, *a*, is cut longitudinally in the face of each, in which slides a tongue, *b*, of the next—these tongues serving as stops when they strike together at the extent of movement of the bars.

At the upper and lower inner edges of the bars are also cut longitudinal groove, *c c*, in which rest the ordinary bearings *d* of slides B B'.

These slides B B' have, in addition to ordinary bearings *d*, central vertical tongues *f*, which extend down between the bars, and serve to separate them from contact with each other.

They also have vertical dovetail or wedge-shaped lugs, *g*, cast on one side of the tongues, which enter corresponding slots cut in the wood, thereby holding in place without screws, which are generally used.

The novelty in this construction consists, essentially, in the tongues *f* and lugs *g*. These tongues, by resting between the bars, separate them, so that

no difficulty can arise from friction in the swelling of the wood.

Very great difficulty is experienced in ordinary extension-tables by the swelling of the wood in damp weather, causing the long contact-surfaces of the bars to adhere, when it is almost impossible to remove them, especially when warped out of place. I obviate all difficulty of the kind, for the bars are perfectly separated their whole length, and the friction-surfaces of the tongues are very small.

The lugs entering the bars at right angles to the motion of the slides, cannot become detached under ordinary circumstances, as the grain of the wood comes in close contact and binds them in place. I thus avoid the necessity of forming screw-holes in the slides, and using screws, which are expensive.

In connection with these slides B B', holding upon the opposite outside edges of the bars, the central blocks or tongues *b*, holding in the grooves *a*, are of importance, as thereby the connection is greatly strengthened, and undue strain is prevented from reaching the outside connections. The central connection holds the vertical strain, while the outside ones hold the horizontal or lateral strain.

By the use of the slides, as above described, it will be noticed that no extra and expensive machinery is required for cutting and fitting the grooves of the bars to receive them, as is the case in the use of many other kinds of slides.

A simple circular saw will cut all the grooves in my bars, since the work is all plain. In others, it is necessary to have special machinery for the purpose.

What I claim as my invention, and desire to secure by Letters Patent, is—

1. The construction of the slides B B', with the central tongues *f*, or equivalent, for separating the bars, and the dovetailed or wedging lugs *g*, for attaching the slides to the wood, substantially as described.

2. In combination with the outside slides B B', the central connection *a b*, substantially as described.

In witness whereof, I have hereunto signed my name, in the presence of two subscribing witnesses.

S. J. GENUNG.
